RADIO RECEIVER CABINET

David Painter, Evanston, Ill., assignor to Avco
Manufacturing Corporation, Cincinnati, Ohio,
a corporation of Delaware

Application October 19, 1949, Serial No. 5,571

Term of patent 3½ years

(Cl. D56—4)

To all whom it may concern:

Be it known that I, David Painter, a citizen of the United States, residing at Evanston, Illinois, in the county of Cook, have invented a new, original, and ornamental Design for a Radio Receiver Cabinet, of which the following is a specification, reference being had to the accompanying drawings, forming a part thereof.

In the drawings:

Fig. 1 is a perspective view of the front and top panels of a radio receiver cabinet showing my new design; and

Fig. 2 is a side elevational view of the radio receiver cabinet shown in Fig. 1.

I claim:

The ornamental design for a radio receiver cabinet, as shown.

DAVID PAINTER.
